Attorney.

UNITED STATES PATENT OFFICE.

LESLIE E. GRABENDIKE, OF RICHLAND CENTER, WISCONSIN.

SHOE-LACE HOLDER.

SPECIFICATION forming part of Letters Patent No. 629,852, dated August 1, 1899.

Application filed September 30, 1898. Serial No. 692,336. (No model.)

To all whom it may concern:

Be it known that I, LESLIE E. GRABENDIKE, a citizen of the United States, residing at Richland Center, in the county of Richland and State of Wisconsin, have invented certain new and useful Improvements in Shoe-Lace Holders; and I do hereby declare the following to be a full, clear, and exact description of the invention, such as will enable others skilled in the art to which it appertains to make and use the same.

This invention relates to improvements in holders for shoe-laces.

The object of the invention is to provide a holder of the class mentioned which is exceedingly simple in its construction and having a minimum number of parts the relation of which is such as to effectually retain a number of shoe-laces or the like in the holder without possibility of the same becoming displaced therefrom.

With this and other objects in view, which will appear as the nature of the improvements is better understood, the invention consists, substantially, in the novel construction, combination, and arrangement of parts, as will be hereinafter described, illustrated in the accompanying drawings, and pointed out in the appended claims.

In the drawings, Figure 1 is a perspective view of a holder constructed in accordance with the present invention. Fig. 2 is a vertical transverse sectional view thereof.

Referring to the drawings, the numeral 1 designates a base-plate which may be provided with a series of attaching-screws 2 or their equivalent, and said plate is adapted to be applied to a wall or similar surface in order that the holder may be suspended therefrom. The plate 1 is also provided at one of its faces with an outwardly-extending hook 3, which is preferably formed integral with the plate 1. The hook 3 is provided at its rear end or that immediately adjacent to the plate 1 with the enlarged head 4, and extending from the lower end of said head is the hook proper, (designated by the numeral 5,) which hook projects upwardly and lies substantially parallel with the front edge of the head 4. The hook 5 is adapted to receive the shoe-laces or similar articles, and pivotally secured to the head 4 by means of a screw 6

or its equivalent is a locking-lever 7. The lever 7 is provided at its rear end with an elongated slot 8, which provides a pair of parallel spaced arms 9, and said arms 9 are perforated at their rear ends and adapted to receive the screw 6, whereby the lever 7 is pivotally connected to the head 4. The hook proper, 5, passes through the slot 8, and the forward end of the lever 7 projects beyond the said hook, thereby providing sufficient weight for said lever, which will cause the latter to gravitate, and consequently bind to a certain extent the laces in the hook 5. A guard-web 10 extends transversely of the slot 8 and is formed integral with the arms 9 at a point intermediate of the ends of said slot, and said guard is adapted to limit the downward movement of the lever 7, and thereby prevent the same from passing below the hook proper, 5. The guard 10 will also prevent the laces from becoming fast between the arms 9 and the hook proper, 5.

The manner of using the herein-described holder is as follows: The lever 7 being swung upwardly a sufficient distance to enable the desired number of laces to be placed in the hook 5, the latter step is taken, and by simply removing the hand from the lever the said lever will gravitate to such a position that the arms 9 thereof bind to a certain extent upon the laces, as clearly shown in the drawings, and thus effectually retain said laces within the hook proper, 5, it being obvious that the laces may be readily withdrawn whenever desired by grasping the same and applying sufficient pressure thereto to remove the laces from beneath the lever 7.

The herein-described invention is not restricted to the use of a shoe-lace holder, but is equally well adapted for holding ribbons and other similar articles, and it is also evident that the same is susceptible of various changes in the form, proportion, and minor details of construction. The right is therefore reserved to modify or vary the invention as falls within the spirit and scope thereof.

Having described my invention, what I claim as new, and desire to secure by Letters Patent, is—

1. A holder of the class described, comprising a hook, and a locking-lever pivoted thereto, said lever being provided with parallel

arms embracing the hook and adapted to bind the articles therein, and also having a guard-web connected to said arms and adapted to contact with the hook for limiting the downward movement of the lever.

2. A holder of the class described, comprising a base-plate, a hook comprising an enlarged head and a hook proper, and a locking-lever having a pair of parallel arms pivotally connected to the enlarged head of the hook and embracing the hook proper, and also pro-

vided with a guard-web adapted to limit the downward movement of the lever, the latter being adapted to gravitate for binding the articles in the hook proper.

In testimony whereof I affix my signature in presence of two witnesses.

LESLIE E. GRABENDIKE.
